JOSEPH A. COYLE, OF AMSTERDAM, NEW YORK, ASSIGNOR, BY MESNE ASSIGNMENTS,
TO BIGELOW-SANFORD CARPET CO., INC., A CORPORATION OF MASSACHUSETTS

PILE-SHEARING MECHANISM FOR PILE-FABRIC-MAKING LOOMS

Application filed March 28, 1928. Serial No. 265,497.

The present invention relates to pile shearing mechanisms for pile fabric making looms and an object thereof is to provide a mechanism which will make it possible to cut the pile closer to the body of the fabric.

To this and other ends the invention consists of certain parts and combinations of parts, all of which will be hereinafter described: the novel features being pointed out

10 in the appended claim.

In the drawings:

Fig. 1 is a side view of the frame of an Axminster loom machine showing the shearing mechanism;

15 Fig. 2 is a plan view of the same parts;

Fig. 3 is a detail view of the mechanism for operating the blades; and

Fig. 4 is an enlarged detail view showing the manner in which the blades operate to

20 cut the pile.

Prior to this invention the shearing mechanism of a loom for making pile fabric has been so constructed that the cutting of a short pile has been impossible, due to the fact, that

25 the shearing mechanism was so constructed that the completed pile surface would interfere with the shearing blades and prevent the blades being brought nearer to the pile fabric. As a result Axminster rugs and car-

30 pets made on looms have had long pile surfaces which have not only required the use of a greater amount of yarn in the material in the pile but have produced a surface which has been objectionable in many respects with

35 the trade, some of objections being the spreading and distortion of the design, the shading of the design and impossibility of bringing out the color variations in the design.

40 According to this invention, it is possible to cut the pile much shorter and to reduce the amount of material in the pile loops. The fabric produced does not spread to distort the design, nor is there any shading effect in the

45 surface. The color variations are brought out by the short compact pile surface and the amount of short free fibers usually present in the pile surface is reduced to a minimum so that the brushing may be reduced in amount

50 or eliminated.

In the illustrated embodiment of the invention, 1 indicates a breast plate over which the finished pile fabric 2 travels. The weaving mechanism for weaving this textile material may be of any suitable construction. 55 The shearing mechanism comes into operation after each operation of "wiping in" the pile forming yarn and severs the "wiped in" portion from the material on the spool.

This shearing mechanism in this embodiment comprises a rear blade 3 and a front blade 4, the former being mounted on a blade carrier 5 and the latter on a blade carrier 6, both carriers being bars extending transversely of the machine and having their ends 60 movable on guides 7 and 8 respectively, arranged at slight angles to each other and adjustable in any suitable manner on the frame of the machine, either to change their angles with reference to the breast plate, or to be 65 moved toward or from the breast plate to cut the pile shorter or longer. The blades 3 and 4 travel in intersecting paths, the front blade passing beneath and cooperating with the underside of the rear blade 3. The edge 70 of the blade 3 is a straight line while the blade 4 from its central portion 10 diverges in opposite directions toward its ends so that a shearing action takes place when the blades 75 cooperate. The blade 3 has its cutting edge, 80 when in cutting position, substantially over the newly "wiped in" portion of the fabric, while the blade 4 operates over the finished portion of the fabric between the blade 3 and the fabric. The under surface of this 85 blade 4 has a bevel 11 which, when in cutting position diverges with reference to the surface of the finished fabric so that it does not engage said fabric in its operation except at the portion to be cut, and thereafter its cutting edge passes toward the unfinished portion of the fabric where there is no pile surface to interfere with its movement.

90 Any suitable means may be employed for effecting relative movement between the two cutters 3 and 4. In this instance, a common drive shaft 12 has three cams thereon, namely a central cam 13 and two end cams 14, the latter two being duplicates of each other. The cam 13 cooperates with a roller 15 on a lever 95 100

16, which has a link 17 pivoted to its outer end, the link also is pivoted to the lower end of a double arm lever 18 pivoted at 19 to the frame of the machine and having its other 5 arm pivotally connected to a link 20 which connects a knife carrier 5 at 21. The cams 14 cooperate with rollers 22 on levers 23 which are pivoted at 24 to the frame of the machine and which have their upper ends pivotally 10 connected to links 25 pivotally connecting at 26 with opposite ends of the knife carrier 6. The cams 13 and 14 are so formed that the knife carrier 5 first advances to cutting position and is held there during the cutting. 15 The knife carrier 6 advances later and causes its knife 4 to engage with the knife 3 and cuts the yarn from the spool as well as trims the fabric to the desired thickness.

From the foregoing it will be seen that 20 there has been provided a pile fabric making loom having a shearing mechanism which is adapted to cut the pile at any desired thickness, making it possible to produce an Axminster rug or carpet having a short compact pile, 25 to reduce the amount of material employed in the pile loops and to obtain a fabric which does not spread or distort the design, has no shading effect and has its color variations brought out distinctly.

30 What I claim as my invention and desire to secure by Letters Patent is:

In combination with a loom of the type for making Axminster carpets or rugs and having a support over which the finished pile 35 fabric is fed, a shearing mechanism comprising two cooperating blades, one of which has its under side in a single plane throughout its width and its upper surface bevelled adjacent its cutting edge, said blade moving over 40 the unfinished portion of the fabric to engage the latest "wiped in" portion of the fabric on the bed and the other of said blades moving over and toward the finished portion of the fabric on the support to engage said latest 45 "wiped in" portion on the bed and engaging the first mentioned blade on the under side of the latter, the second blade having its upper surface in a single plane throughout its width and its lower surface bevelled adjacent its 50 cutting edge and diverging from its cutting edge relatively to the finished portion in immediate proximity to said "wiped in" portion so as not to engage the finished portion except at the latest "wiped in" portion.

55 JOSEPH A. COYLE.
